UNITED STATES PATENT OFFICE

169,739

COOKING PAN LID

Ralph J. Dietrich, Palm Springs, Calif.

Application September 27, 1952, Serial No. 21,622

Term of patent 3½ years

(Cl. D44—15)

To all whom it may concern:

Be it known that I, Ralph J. Dietrich, a citizen of the United States, residing at Palm Springs, California, have invented a new, original, and ornamental Design for a Cooking Pan Lid, of which the following is a specification, reference being had to the accompanying drawing, forming a part hereof.

Fig. 1 is a plan view of a cooking pan lid showing my new design;

Fig. 2 is a front elevational view of Fig. 1; and

Fig. 3 is a cross-section on line 3—3 of Fig. 1.

The dominant features of my design reside in the portions shown in full lines.

I claim:

The ornamental design for a cooking pan lid, substantially as shown and described.

RALPH J. DIETRICH.
